UNITED STATES PATENT OFFICE

WILLEM HONDIUS BOLDINGH, OF EINDHOVEN, NETHERLANDS

DESIGN FOR AN X-RAY AGGREGATE

Application filed June 7, 1930, Serial No. 35,977, and in Switzerland February 26, 1930. Term of patent 14 years.

To all whom it may concern:

Be it known that WILLEM HONDIUS BOLDINGH, subject-citizen of the Queen of the Netherlands, residing at Eindhoven, in the Kingdom of the Netherlands, has invented a new, original, and ornamental Design for an X-ray Aggregate, of which the following is a specification, reference being had to the accompanying drawing, forming part thereof.

The figure is a view of an aggregate for dentists to be used in connection with an X-ray tube showing the new design, the side of the design opposite to that illustrated in the drawing being substantially the same as that pictured therein.

I claim:

The ornamental design for an X-ray aggregate for dentists as shown and described.
WILLEM HONDIUS BOLDINGH.
